UNITED STATES PATENT OFFICE.

ROBERT E. BAKER, OF CLEVELAND, OHIO.

STORAGE-BIN.

1,088,762.

Specification of Letters Patent.

Patented Mar. 3, 1914.

Application filed May 23, 1912. Serial No. 699,118.

To all whom it may concern:

Be it known that I, ROBERT E. BAKER, a citizen of the United States, a resident of Cleveland, county of Cuyahoga, and State of Ohio, have invented a new and useful Improvement in Storage-Bins, of which the following is a specification, the principle of the invention being herein explained, and the best mode in which I have contemplated applying that principle, so as to distinguish it from other inventions.

My invention relates to storage bins or receptacles for a like purpose, such as are used for storing iron-ore, coal or similar materials in bulk, its object being to provide a bin-structure which will be economical in its construction and efficient in its operation.

A particular object of the invention is to provide a bin construction in which materials composing the bottom and sides are so disposed as to resist by their tensile strength, the stresses due to the imposed loads; and in which all of the contents may be discharged by gravity alone.

Bins characterized by said resisting feature, are commonly known to those skilled in the art, as "suspension bins." It has heretofore been common practice to construct bins of this type having sides and bottom

substantially parabolic in cross-section, and while such bins have been found to be efficient in their disposal of materials forming the sides and bottoms thereof, in so far as concerns the resistance of strains due to the imposed loads, they do not, owing to the necessarily comparatively flat or horizontal form of their bottoms, permit at all times, an easy flow of the contained material, inasmuch as there is a tendency, in conse-

quence, toward an increasingly sluggish movement of the material as the bottom is approached. In the full parabolic form of construction it is the usual practice to provide discharge openings at intervals in the bottom, so spaced as to retain between them a sufficient section of the material forming such bottom, to insure adequate transverse strength to support, without rupture, the load imposed by the stored material. These

two elements in such parabolic form of bins, *i. e.*, the comparatively flat bottom and the necessary provision or retention of considerable structural material between the discharge openings makes it impossible to completely discharge the contents of such bins by gravity alone, and manual labor or other

extraneous means must hence be provided for that purpose.

In my improved construction the advantageous disposition of the structural elements of the sides and bottoms of the former bin-construction is retained, and the disadvantages attendant upon the peculiar form of the bottoms thereof have been eliminated.

A further particular object is to provide a construction which may be readily erected in the field without the necessity of riveting, thus eliminating in the field the use of riveting machines, whereby such erection is much simplified and the economy of erection greatly increased.

A further specific object is to provide a construction in which the worn or defective parts may be removed and replaced in a simple, economical and efficient manner.

The said invention consists of means hereinafter fully described and particularly set forth in the claims.

The annexed drawings and the following description set forth in detail a certain construction embodying my invention, the disclosed construction, however, constituting but one of various mechanical forms in which the principles of my invention may be applied.

In said annexed drawings: Figure 1 is a vertical transverse section of a storage-bin embodying my invention. Fig. 1^a is an enlarged transverse section of a fragmentary portion thereof. Fig. 2 is a front elevation, with parts of the supporting-frame broken away, of a fragmentary portion of such bin, showing two complete bays. Fig. 2^a is an enlarged front elevation of a fragmentary part of such bin. Fig. 3 is a longitudinal vertical section of a fragmentary part of the bin, showing a complete bay. Figs. 4 and 5 are perspective views of one of the longitudinal and end elements, respectively, of the intermediate-structure of the bin. Fig. 6 is a detail enlarged section taken upon the plane indicated by line VI—VI, Fig. 1. Fig. 7 is a detail enlarged section of a modification of one feature of my improved bin.

The illustrated embodiment of my invention comprises three main parts, namely; a supporting-structure, a bottom-structure and an intermediate-structure.

The frame-portion of the supporting-structure may be of any suitable form designed to carry or suspend the weight of the

bin and its contents. In the drawings I have illustrated this frame-portion as consisting of reinforced concrete elements; including the vertical pillars A A; the longitudinal beams or girders B B, supported on the top of said pillars; and the transverse girders C C, also supported on the top of said pillars; the system of reinforcement being indicated by dotted lines but forming no part 10 of my present invention. It is obvious that structural steel elements may be substituted for the reinforced concrete elements, but the latter have been selected as illustrating one particular form of elements of the many possible forms which may be adopted for constructing the required supporting-frame.

The girders B B are placed so as to incline inwardly, as shown, at substantially the required angle and have formed therein centrally disposed apertures b b, Fig. 1, equidistant from each other in each bay and in the longitudinal direction of the girders as shown in Fig. 2. These apertures are made to increase in diameter from the top downwardly for a purpose hereinafter particularly set forth.

Forming the supporting-structure in combination with the frame, and passing through the apertures b b, are rods D D, threaded at both ends. The upper ends are prevented from passing through the apertures by means of nuts d and washer-plates d', the latter resting upon the upper surface of the girders, such surfaces having an inclination of an angle complementary to that of the inclination of the girders, as will be understood. The smaller diameter of said apertures is made such that the rods may be easily inserted or withdrawn therefrom.

40 The entire bin-structure, as illustrated, is divided into bays, equal in length to the distance between centers of the pillars A A. The two sets of rods so provided and supported form the direct support for the bottom-structure E. The latter is formed in sections equal in length to the bays and each section, excepting the extreme left-hand section, consists of the rear plate e, the front plate e' and an end plate or diaphragm e². 45 These plates are permanently secured to each other by means of angle-bars e³ e³, secured to the inner adjacent surfaces of said plates, by means of rivets. The rivet-holes in the angle-bars are made conical or countersunk at the upper surface of such bars so that the rivets may be made flush with the latter, as is the usual practice in order to prevent abrasion thereof which would otherwise be caused by the movement of the material in the bin, and to eliminate all elements tending to impede the flow of such material.

To the bottom of the right-hand end of each plate e and e' of each such bottom-section is riveted a connecting-plate e⁴, Fig. 2.

which plates extend beyond the ends of the sections, and are secured by the same rivets as secure the angle-bars e³ e³ to the said plates e and e'.

The several bottom-sections, when placed in position end to end, as will be hereinafter described, have their abutting ends secured to each other by means of bolts e⁵ having conical heads set in countersunk holes in angle-bars e⁶, Fig. 2^a, said bolts passing through the plates e and e', and through connecting-plates e⁴, as will be readily understood. The angle-bars e⁶ are not connected with the end-plates or diaphragms e², and hence merely serve to reinforce the left-hand ends of plates e and e' and to hold the lower-edge portions of said diaphragms against movement away from angle-bars e³ e³.

The extreme left-hand bottom-section is provided with an additional end-plate (not shown) as will be understood, forming the left-hand end of the bottom-structure of the bin. The diaphragm e² of the right-hand bottom-section, it will be likewise understood, forms the right-hand end of the bottom-structure.

Each plate e' is formed with a plurality of discharge-openings controlled by suitable doors E', and secondary diaphragms e⁷ are provided, as shown in Fig. 3, subdividing each bottom-section, and permanently secured by suitably riveting. The diaphragms form transverse ties which render each bottom-section, and hence the entire bottom-structure substantially rigid.

Near the upper edge of each of the plates e and e' of each bottom-section, are secured by suitably riveting, two longitudinally extending angle-bars e⁸ and e⁸, placed back to back, as shown in Figs. 1 and 2^a, so as to form a strong and rigid projecting flange, e⁹. These flanges are formed with a plurality of holes which are spaced so as to receive the rods D D. Above the said flanges, and forming the edge-portions of the sides of the bottom-sections, are the angle-bars e¹⁰ and e¹⁰, formed with a plurality of enlarged holes in alignment with the holes in flanges e⁸ and e⁸, and also provided for receiving the rods D D. Resting upon the upper faces of the angle-bars e⁸ and e⁸, and upon the upper edge of the diaphragms e² and e² is the intermediate-structure F. This structure consists of a plurality of sections each formed of a rear longitudinal and flexible plate f, a front longitudinal and flexible plate f', and the end-plates or diaphragms f². The plates f and f' lie and rest against the inside of the bars D, as shown in Figs. 1 and 1^a. Each diaphragm f² has riveted upon opposite sides of its lower edge-portions, the downwardly projecting bars e¹¹ and e¹¹, forming a groove e¹². These diaphragms

f^2 rest upon the upper edge of the diaphragms e^2 and e^2 in grooves e^{12} , and are held against horizontal displacement by the bars e^{11} and e^{11} . The lower edge-portions 5 of plates f and f' are provided with the outwardly projecting and permanently secured angle-bars f^3 , which rest upon the angle-bars e^{10} , as shown in Figs. 1 and 2^a. Said bars f^3 are provided with open slots 10 f^4 and f^4 , registering with the enlarged holes in bars e^{10} and e^{10} , for receiving the rods D D, and with suitable bolt-holes for receiving the bolts f^5 which pass through the said bars e^{10} , whereby the plates f' may be 15 removably secured to the bottom-structure as will be understood and as is illustrated in Fig. 2^a.

The lateral edge portions of the plates f and f' are provided with the permanently secured and outwardly projecting riveted angle-bars f^6 , as shown in Fig. 4. The diaphragms f^2 are of dimensions such that they project between the angle-bars f^6 and f^6 and are secured therebetween by means of 25 bolts f^7 , and their upper edge-portions are reinforced by stiffening members f^8 , as shown in Fig. 5. The lower part of each diaphragm is further provided with extensions f^9 to which struts or braces G supported by pillars A, Fig. 1, are removably 30 and pivotally secured by means of bolts g secured in place by means of split pins g , Fig. 1^a.

As in the case of the riveting of the angle-bars e^3 to the diaphragms e^2 and plates e' , all other riveting above referred to is effected in connection with countersunk holes on the inside of the structure as is customary.

The bottom-structure together with the intermediate-structure form a container-member which is attached to the direct supporting-means (the rods) in a horizontal plane below the plane of the container-member's top, such member being free from such attachment in all intermediate horizontal planes.

In constructing the above described bin, the bottom-sections are each assembled in the shop before being transported to the field. The plates f and f' and the diaphragms f^2 are also built with their parts riveted thereto, in the shop. It will therefore be seen that no riveting is required in the field. The frame having been first 55 erected, the rods D are placed in position in the apertures b , with the lower nuts detached. The bottom-sections are placed end to end, their abutting ends secured by means of the plates e^4 and the bolts e^5 , thus completely assembling the entire bottom-structure. The bottom-structure is then raised and the lower ends of the rods D passed through the angle-bars e^{10} and the flanges e^9 , whereupon the nuts are placed upon such lower ends and the said section thus sus-

pended. The said rods are made of a length sufficient to permit these sections to occupy a lower position than that which they occupy finally in the completely assembled structure, and they are permitted to at first 70 occupy such lower position. The plates f and f' are now passed downwardly from above and caused to assume their positions resting upon the angle-bars e^{10} , the open slots f^4 permitting them to assume these positions. These plates are now secured to the bottom-structure by means of bolts f^5 . One of the diaphragms f^2 is first placed in position. The next diaphragm f^2 is now placed 75 in position and both diaphragms are secured to the angle-bars f^6 by means of the bolts f^7 . This having been accomplished, the bottom-structure, supporting the intermediate-structure consisting of plates f and f' and diaphragms f^2 is raised by turning the nuts 80 upon the lower ends of the rods D, until the edges of the diaphragms engage the under side of the girders C C, and the structure thus completed. It will be hence seen that by means of the above described arrangement, all bolt-heads and nuts are upon the outside, with the exception of the heads of bolts e^5 (and these heads are in countersunk holes) and are therefore not subject to the abrasive action and do not impede the 85 flow of the material in the bin. Furthermore, any of the bottom-sections may be removed for repairs or replacement, and any element of the intermediate-structure may 90 be removed and replaced.

When the bin is filled with material, the latter tends to bend the plates f and f' outwardly, and in horizontal planes, particularly at the central portion thereof. The rods, therefore, may act as a support for 105 said plates when the latter are so bent, and act as a reinforcement therefor against the action of the bending force. If such force is great enough to bend these rods, the upper and also the lower nuts, act as pivots. This 110 pivotal movement is permitted by making the openings b of the described enlarged form and by the enlargement of the holes in the angle-bars e^{10} .

In designing my improved bin for use in 115 connection with certain classes of bulk material, I have found that the angle-bars f^6 and f^6 may be omitted, if desired, and the diaphragms f^2 permitted to be free from connection with the plates f and f' . In such 120 event, the latter would tend to bend outwardly to the same degree in any given intersecting horizontal plane.

The provision of a rigid bottom-structure 125 suspended from the supporting-structure by means of a direct support, such as the rods, makes it possible to have a continuous opening between the vertical planes of the faces of the diaphragms or ties e^7 , thus eliminating completely any element having faces or 130

parts projecting transversely of the flow of the material downwardly in the bottom-structure. The sides of the latter may also be given the desired inclination. These two features, therefore, make it possible to discharge the entire contents of the bin by gravity solely.

Instead of providing each bottom-section (with the exception of the one end section which is provided with two such diaphragms as hereinbefore described) with but a single diaphragm e^2 , each such section may be provided with two such diaphragms e^2 , as illustrated in Fig. 7. In such event, the two end diaphragms abut each other in every bay, and the downwardly projecting bars e^{11} and e^{12} are bent so as to increase the width of the groove e^{12} in order that these bars may span and secure between them such two abutting diaphragms, as will be readily understood. I have also found it advisable to provide plates, H, Fig. 6, which are placed against the outside of the rods D, and are secured to the plates f and f' by means of bolts h , with their heads upon the interior. The plates f and f' , after coming from the shop, are usually in a bent or buckled condition, and these plates H and bolts are provided to straighten them when they are placed in position against the rods. Said plates H, however, are not drawn up against the rods D to a degree such as will cause the said rods and plates f and f' to bind, thus allowing said rods to move freely with reference to plates f and f' when the flexing of the latter takes place as a result of the imposed loads, as hereinbefore described.

Having fully described my invention, what I claim and desire to secure by Letters Patent is:

1. A suspension storage bin comprising a supporting structure, flexible tension members suspended from said supporting structure, a rigid bottom structure supported by said tension members, and a side structure supported by said bottom structure and resting against said tension members.

2. A suspension storage bin comprising a supporting structure, flexible tension members suspended from said supporting structure, a bottom structure supported by said tension members, and flexible plates supported by said bottom structure and resting against said tension members.

3. A suspension storage bin comprising a rectangular supporting structure, the side members of which are sloped in the direction of the load thereon, flexible tension members depending inwardly therefrom and in approximately the same plane therewith, a rigid bottom structure supported by said flexible members, and flexible side containing members supported by said bottom structure and resting against said tension members.

4. A suspension storage bin comprising a supporting structure, flexible tension members suspended from said supporting structure, a rigid bottom structure supported by said flexible tension members, and transverse tension members separating said bottom structure into chutes, said flexible tension members and flexible side containing members being free to assume shape approximating a segment of a parabola under imposed load.

5. A suspension storage bin comprising a supporting structure, flexible tension members depending therefrom, a rigid bottom structure supported by said flexible tension members, flexible side containing members resting against said flexible tension members, and end containing members resting on said rigid bottom structure and rigidly attached to said flexible side containing members.

6. In a storage-bin, the combination of a supporting-frame; two sets of depending rods converging downwardly and loosely mounted upon said frame; a bottom-structure suspended by said rods; and an intermediate-structure supported on said bottom-structure; said bottom-structure having its two opposite sides secured to said two sets of rods respectively.

7. In a storage-bin, the combination of a supporting-structure; a rigid bottom-structure suspended from said supporting structure; and an intermediate-structure suitably supported, free to flex outwardly so as to assume a position in which internal strains, due to the imposed load, will be resisted by the tensile strength of said supporting means.

Signed by me this 20th day of May, 1912.
ROBERT E. BAKER.
